UNITED STATES PATENT OFFICE.

CHARLES PAFF, OF NEW YORK, N. Y.

METALLIC TIE.

1,330,276.

Specification of Letters Patent.

Patented Feb. 10, 1920.

Application filed May 21, 1918. Serial No. 235,822.

To all whom it may concern:

Be it known that I, CHARLES PAFF, a citizen of the United States, and a resident of New York, in the county of New York and State of New York, have invented a certain new and useful Improvement in Metallic Ties, of which the following is a full, clear, and exact specification.

This invention relates more particularly to a class of devices adapted to be used in conjunction with the rails for cars.

My invention has for its object primarily to provide a tie designed to be employed for holding and supporting the rails on a railroad bed, and which is of metal, in order to replace the use of ties made of wood as well as being of a form whereby the resiliency required of the functioning of this class of ties is provided, besides being constructed so as to combine unusual strength and durability. The invention consists essentially of an elongated body formed of sheet metal bent lengthwise to provide one or a number of inverted substantially U-shaped members in cross section which are disposed in spaced parallel arrangement, and at one end the opposed arms of these members are bridged by a plate which serves to support the members when laid on a railroad bed as well as serving as a spring actuating element to cause the members to yieldingly function when under the pressure of a load.

Other objects of the invention are to provide in the side walls of each of the U-shaped members besides providing in the spring supporting element corrugations or ribs whereby these parts of the ties will be strengthened; and to provide openings or entrances at the ends of each member of the body to allow ballast to be tamped into the members.

With these and other objects in view, the invention will be hereinafter more particularly described with reference to the accompanying drawing forming a part of this specification in which similar characters of reference indicate corresponding parts in all the views, and will then be pointed out in the claims at the end of the description.

In the drawing, Figure 1 is fragmentary view showing a top plan of a number of my improved metallic ties as employed for supporting car rails.

Fig. 2 is a detail sectional view taken on the line 2—2 of Fig. 1.

Fig. 3 is a detail end view.

Fig. 4 is a detail sectional view taken on the line 4—4 of Fig. 2.

Fig. 5 is a detail sectional view taken on the line 5—5 of Fig. 2, and

Fig. 6 is an enlarged fragmentary sectional view showing in perspective a portion of a railway rail with adjacent parts of one of the tie members with the form of clip employed for fastening the rail on the tie.

The device or tie has an elongated body 10 which is made of sheet spring metal bent lengthwise to provide one or a number of members, though in the drawing a form of the body is illustrated which shows two of the members, as 11 and 12. Both of these members are of similar formation, and each member is of the shape substantially of an inverted U in cross section to provide two side arms or legs 13 and 14 and a top plate 15 which is preferably somewhat flat. The upper lengthwise edges of each of the U-shaped members may be slightly rounded, as shown, and the arm 14 of one member, 80 and the arm 13 of the other member may be somewhat shorter than the second arms of the members. The members 11 and 12 of the body 10 are relatively disposed at some distance apart in parallel arrangement, and the lower ends of the opposed arms 13 and 14 of the members are connected or bridged by a cross plate, as 16. By making the plate of sufficient width a yielding functioning of the members 11 and 12 in upward and downward directions when under the pressure of a load will be provided, and this cross plate also serves as a supporting element when the tie is laid on a railroad bed by contacting with the bed. The free edge of the arm 13 of the U-shaped member 11 of the body 10 may be flanged or beaded lengthwise, as at 17, while the free end of the arm 14 of the U-shaped member 12 is flanged or beaded lengthwise, as at 18. The arm 13 of the member 11 may also be transversely corrugated, or fluted or ribbed, as at 19, and the arm 14 of the member 12 may be likewise corrugated, or fluted or ribbed, as at 20,

while the arm 13 of the member 11, the arm 14 of the member 12 as well as the plate 16 may be corrugated, or fluted or ribbed, as at 21, in order to reinforce the strength of the

U-shaped members as well as the plate 16 when the tie is made of comparatively thin sheet metal. Moreover, these corrugations tend to impart a yielding functioning of the end portions of the members of the tie.

At spaced intervals through the length of the body 10 the arms of the U-shaped members 11 and 12 may be tied by means of rods or bars, as 22, 23, 24, which pass through registering openings in the arms so as to be disposed across the recesses of the members and across the plate 16 between the members. In the top plate 15 at one end of each of the members of the body 10 is an opening 25, and in this top plate at the other end of each member is a second opening 26. The openings 25 and 26 may be provided by cutting out accordingly the top plate and then striking downwardly, as at 27 and 28, respectively, the cut portions of the top plate for partially or entirely closing the ends of the members, these openings serving to allow ballast to be tamped into the hollow underside of the members 11 and 12 when the tie is laid on a railroad bed. In practice a number of the ties are laid in suitable spaced relation on a railroad bed in a manner similar to the arrangement of the ordinary forms of wood ties so that the plate 16 of each tie will rest upon the bed while the recessed or hollow undersides of the U-shaped members 11 and 12 of the body 10 are filled with ballast. On the top plates 15 of the members 11 and 12 are then disposed in the usual fashion the car rails, as 29 and 30, and to allow the rails to be fastened to the members, I provide forms of clips 31 and 32 as disclosed in my pending application, serially numbered 239,570, filed June 12, 1918. In order to permit the clips to be employed, on the top plate 15 of each of the U-shaped members 11 and 12 of the body 10 and suitably spaced from the base flange of the rail, are provided lugs, as 33 and 34. Each of these lugs is formed preferably by cutting out the required portions of the top plate, and striking upwardly the cut-out parts in somewhat the fashion of an inverted L so that the longitudinal arm of each lug will protrude toward the base flange of the rail. Thus a very simple, efficient and durable metallic tie is provided for railway rails to replace the use of wood ties.

In the foregoing description, I have embodied the preferred form of my invention, but I do not wish to be understood as limiting myself thereto as I am aware that modi-

fications may be made therein without departing from the principle or sacrificing any of the advantages of this invention, therefore I reserve to myself the right to make such changes as fairly fall within the scope thereof.

Having thus described my invention, I claim as new and desire to secure by Letters Patent:—

1. A metallic tie formed of sheet metal to provide an elongated body including two spaced parallel members, and a spring element between the members whereby said members will be yieldingly movable lengthwise upwardly and downwardly.

2. A metallic tie formed of sheet metal to provide an elongated body including two spaced parallel members each of substantially an inverted U-shape in cross section, and a spring element between the opposed arms of the members whereby said members will be yieldingly movable lengthwise upwardly and downwardly.

3. A metallic tie formed of sheet metal to provide an elongated body including two spaced parallel members each of substantially an inverted U-shape in cross section, and a yielding plate between the opposed arms of the members, each of said members having an opening at each of its ends.

4. A metallic tie formed of sheet metal to provide an elongated body of substantially an inverted U-shape in cross section, each arm of the body being corrugated and the body having an opening in the top of each of its ends, and a plate closing each end of the body.

5. A metallic tie formed of sheet metal to provide an elongated body including two spaced parallel members each of substantially an inverted U-shape in cross section, and a yielding plate between the opposed arms of the members, said plate as well as the arms of each member being transversely corrugated, and spaced bars connecting all of the arms of the members.

6. A metallic tie formed of sheet metal to provide an elongated body including two spaced parallel members each of substantially an inverted U-shape in cross section, and a yielding plate between the opposed arms of the members, said plate as well as the arms of each member being transversely corrugated, and each member having an opening in its top at each of its ends.

In testimony whereof I affix my signature.

CHARLES PAFF.
